UNITED STATES PATENT OFFICE.

WALTER L. BADGER, OF ANN ARBOR, MICHIGAN, ASSIGNOR TO SWENSON EVAPORATOR COMPANY, OF HARVEY, ILLINOIS, A CORPORATION OF ILLINOIS.

EVAPORATING APPARATUS.

Application filed May 19, 1924. Serial No. 714,512.

This invention relates generally to closures and refers more particularly to covers designed for closing the ends of the heating cylinders of vacuum evaporating apparatus and the like such as illustrated for example by the patent to Yaryan No. 383,384, dated May 22, 1888.

One of the essential objects of the invention is to provide a cover of this type having passages for connecting pairs of the usual evaporating tubes within the cylinder to form coils in which the liquid is adapted to flow freely.

Another object is to provide a cover that carries a feed box for receiving the liquid to be treated and that also carries a plurality of distributing pipes for conveying the liquid from the feed box to the inlet ends of the coils in the cylinder.

With the above and other objects in view the invention consists in certain novel features of construction, combinations and arrangements of parts as will be more fully described and particularly pointed out in the appended claims.

In the accompanying drawing:

Figure 1 is a front elevation of a cover embodying my invention mounted upon a cylinder of a vacuum heating apparatus;

Figure 2 is a fragmentary side elevation thereof;

Figure 3 is a top plan view thereof;

Figure 4 is an enlarged detail view;

Figure 5 is an enlarged fragmentary top plan view of the construction shown in Figure 3.

Describing in detail the particular embodiment of my invention shown in the drawings, the reference character 1 designates a cylinder, preferably of a vacuum evaporating apparatus having a head 2 supporting a plurality of spaced open-ended evaporating tubes 3 that extend longitudinally of the cylinder. These tubes may be secured in any suitable way to the head, and the latter may be secured by any suitable means to the cylinder. As shown, the ends of the tubes 3 are preferably expanded in suitable openings 4 in the head 2 and the latter are preferably detachably secured by means of screws 5 to a flange 6 at the forward edge of a collar 7 that is riveted to the cylinder.

Heretofore, the heating cylinders of this type of vacuum evaporating apparatus have

been provided with covers in the form of plates that were provided with flanges for connecting pairs of the evaporating tubes to form coils and were detachably secured to the cylinder heads by means of bolts, screws 60 and the like. Usually, with such constructions, the pipes or other conduits for supplying the liquid to be treated to the evaporating coils within the cylinder were coupled to tubes carried by the cover so that the 65 pipes could be uncoupled from the tubes when it was desired to detach the cover from the cylinder head. However, the return bends provided by the flanges on the covers cause eddies to be formed in the liquid so 70 that the flow from one tube to another is restrained. Moreover, considerable time and labor is required to adjust the separate couplings and the many nuts or bolts or other securing elements for the cover whenever it is desired to attach or detach the same.

With the present invention, the objectionable features just referred to are overcome entirely, and I preferably provide a 80 cover 8 that is swingingly mounted upon the collar 7 secured to the cylinder and that is provided with curved passages 9 for connecting pairs of the tubes 3 to form coils through which the liquid to be treated may 85 flow. As shown, the cover 8 is preferably provided with spaced arms 10 that are preferably connected to spaced arms 11 projecting from the collar 7 by means of a vertical bolt 12. In order that the liquid will have 90 a stream line flow from one tube to another, the cross sectional area of the inlet ends 13 of the passages is greater than the cross sectional area of the discharge ends 14 of the tubes and the cross sectional area of the 95 outlet ends 15 of the passages is less than the cross sectional area of the inlet ends 16 of the tubes. To prevent leakage when the cover is closed, the expanded ends of the tubes 3 preferably project slightly beyond 100 the outer face of the head 2 and enter suitable recesses 17 in the inner face of the cover 8, while a suitable yieldable gasket 18 is secured to the outer face of the head 2 and cooperates with the inner face of the cover 105 when the latter is closed to form a seal. Any suitable means such as a screw 19 extending through the head 2 may be employed for holding the cover 8 in closed position.

For supplying the liquid to be treated to 110

the inlet ends 20 of the coils within the cylinder, I preferably provide a plurality of pipes 21 that have vertical portions 22 connected at their lower ends to a feed box 24 located at the lower end of the cover 8, and that have horizontal portions 25 which are connected to the vertical portions 22 by suitable couplings 26 and extend through the cover 8 at the proper points for registering with the inlet ends of the coils when the cover is closed. The feed box 24 is preferably formed integral with the cover 8 and is provided with an inlet opening 27 which, when the cover is closed, is adapted to register with the free end of a suitable supply pipe 28 extending through the flange 6 and head 2 secured to the cylinder. Any suitable means (not shown) may be employed for regulating the supply of liquid conveyed 20 through the pipe 28 to the feed box.

To prevent any foreign matter from passing from the feed box 24 to the coils within the cylinder, I preferably provide a suitable strainer in the form of a foraminous plate 29 that is supported upon horizontal flanges 30 projecting inwardly from the inner walls of the feed box.

From the foregoing description, it will be readily apparent that I have provided an extremely simple and practical construction in which the cover forms a common support for the feed box and distributing pipes. Inasmuch as the cover is swingingly mounted on the cylinder, it will also be apparent that the cover, feed box and distributing pipes 25 may be readily moved as a unit to either open or closed position with respect to the cylinder head whenever desired. Furthermore, the connection between the tubes within 40 the cylinder is such that the liquid will have a stream line flow from one tube to another. This is particularly desirable in an apparatus of the kind described.

What I claim as my invention is:

1. The combination with a cylinder having a head and a plurality of tubes in the cylinder extending through the head, of a cover connected to the cylinder having passages therein for connecting pairs of said tubes to form coils, the cross sectional area of the inlet ends of the passages being greater than the cross sectional area of the discharge ends of the tubes and the cross sectional area of the outlet ends of the passages being less than the cross sectional area of the inlet ends of the tubes.

2. The combination with a cylinder having a head and a plurality of tubes in the cylinder extending through the head, of a cover having passages therein for connecting pairs of said tubes to form coils, a feed box integral with said cover, and means for pivotally connecting said cover to said cylinder.

3. The combination with a cylinder having a head and a plurality of tubes in the cyl-

inder extending through the head, of a cover having passages therein for connecting pairs of said tubes to form coils, a feed box integral with said cover, arms projecting from the cover, arms projecting from the cylinder, and a pivot member connecting the last-mentioned arms to the first-mentioned arms.

4. The combination with a cylinder having a head and a plurality of tubes in the cylinder extending through the head, of a cover connected to the cylinder having passages therein and connecting pairs of said tubes, a liquid feed box carried by the cover, means for conducting liquid from the feed box to said passages, and means for connecting the cover to the cylinder whereby the cover liquid conducting means and feed box may be moved as a unit.

5. The combination with a cylinder having a head and a plurality of tubes in the cylinder extending through the head, of a cover connected to the cylinder having passages therein for connecting pairs of said tubes to form coils, a liquid feed box carried by the cover, and distributing pipes carried by the cover for conveying the liquid from the feed box to the inlet ends of the coils aforesaid.

6. The combination with a cylinder having a head and a plurality of tubes in the cylinder extending through the head, of a cover connected to the cylinder having passages therein for connecting pairs of said tubes to form coils, a liquid feed box carried by the cover, means carried by the cylinder head for conveying the liquid to the feed box, and means carried by the cover for conveying the liquid from the feed box to the inlet ends of the coils aforesaid.

7. The combination with a cylinder having a head and a plurality of tubes in the cylinder extending through the head, of a cover connected to the cylinder having passages therein for connecting pairs of said tubes to form coils, a liquid feed box carried by the cover, a supply pipe carried by the cylinder head for conveying the liquid to the feed box said feed box having an inlet opening adapted to register with the discharge end of said supply pipe when said cover is closed, and means carried by the cover for conveying the liquid from the feed box to the inlet ends of the coils aforesaid.

8. In a vacuum evaporating apparatus, the combination with a cylinder having a head, and a plurality of tubes in the cylinder extending through the head, of a cover connected to the cylinder, a liquid feed box carried by the cover, means for supplying a liquid to the feed box, and means carried by the cover for conveying the liquid from the feed box to certain of the tubes in the cylinder.

9. In combination with a cylinder having

a head and a plurality of tubes in the cylinder extending through the head, of a cover connected to the cylinder having passages therein for connecting pairs of said tubes to form coils, the cross sectional area of said passages being greater at the inlet than at the discharge thereof.

10. The combination with a cylinder having a head and a plurality of tubes in the cylinder extending through the head, of a cover having passages therein for connecting pairs of said tubes to form coils, an inlet conduit for supplying fluid to said passages of the cover, and means for detachably connecting said cover and cylinder whereby the cover may be removed without disturbing said inlet conduit.

11. The combination with a cylinder having a head and a plurality of tubes in the cylinder extending through the head, of a cover having passages therein for connecting pairs of said tubes to form coils, means for pivotally mounting said cover whereby the latter may be swung away from the cylinder head, a supply conduit secured to said head for conducting liquid to said tubes, said supply conduit automatically breaking joint with said cover when the cover is swung on its pivot.

12. The combination with a cylinder having a head and a plurality of tubes in the cylinder extending through the head, of a cover having passages therein for connecting pairs of said tubes to form coils, a feed box carried by the cover, means for pivotally mounting said cover whereby the latter may be swung away from the cylinder head, a supply conduit for conducting liquid to said feed box, distributing pipes carried by the cover for conducting liquid from the feed box to the said tubes, said supply conduit and passages automatically breaking joint with said cover when the cover is swung on its pivot.

13. The combination with a cylinder having a head and a plurality of tubes in the cylinder extending through the head, of a cover pivotally connected to the cylinder having passages therein for connecting pairs of tubes to form coils, a relatively stationary fluid supply conduit secured in said head, means associated with said cover for supplying fluid from the supply conduit to said tubes, said supply conduit automatically breaking joint with said means upon a pivotal movement of the cover.

In testimony whereof I affix my signature.
WALTER L. BADGER.
